GRINDING AND POLISHING APPARATUS

William R. Akans, Homewood, Ala.

Application August 27, 1936, Serial No. 98,177

2 Claims.

(Cl. 51—197)

My invention relates to grinding and polishing apparatus and contemplates the provision of apparatus of this kind adapted for use in producing highly finished surfaces on valve seats and the like, and has for an object the provision of a device which may be readily mounted in a drill press, boring mill, or the like for rotational movement to grind or polish surfaces.

My invention further contemplates the provision of a device of this kind provided with flexible coupling means adapted to overcome inaccuracy in the alignment of the work in the machine.

My invention further contemplates the provision of a grinding and polishing apparatus embodying means by which the working pressure of the finishing elements upon the work may be readily regulated by the operator.

My invention further contemplates the provision of grinding and polishing apparatus in which the plate bearing the finishing elements is removable therefrom for assembly therewith inside a valve.

My invention further contemplates the provision of a grinding and polishing apparatus provided with improved means for mounting the finishing material, such as cloth covered with abrasive material, in working position on the device.

My invention embodies other novel features, details of construction, and arrangement of parts which are hereinafter set forth in the specification and claims and shown in the accompanying drawing.

Apparatus embodying features of my invention is illustrated in the accompanying drawing, forming part of this application, wherein:

Fig. 1 is a view in side elevation of my improved grinding and polishing device, the plate employed to carry the finishing elements being removed therefrom;

Fig. 2 is a sectional view taken along the line II—II of Fig. 3, showing the working plate having a pair of finishing members attached thereon;

Fig. 3 is a plan view of the working plate;

Fig. 4 is a sectional view taken along the line IV—IV of Fig. 1;

Fig. 5 is a sectional view taken along the line V—V of Fig. 1;

Fig. 6 is a sectional view taken along the line VI—VI of Fig. 2; and

Fig. 7 is a sectional view taken along the line VII—VII of Fig. 4.

Referring now to the drawing for a better understanding of my invention, I show a grinding

and polishing apparatus comprising a shaft 3 which is adapted to be rotated by any suitable means. On the lower end of the shaft is formed a shoulder or flange portion 9 which is snugly fitted for movement in a recess 11 formed in the attachment plate 12. The attachment plate is provided with an inwardly turned flange portion 10 for engagement with the shoulder 9 when same is in its upper position.

The shaft is slotted at 13 above the shoulder portion 9 to receive a driving plate 14 which rests upon the flange 10 and between the projections 16 of the attachment plate. A pivot point 17 is also mounted in the slot 13 and is held against displacement by a collar 18 which forms a spring seat for the lower end of the spring 19. A sleeve 21 is secured to the upper end of the shaft by means of the set screw 22 and is threaded at 23 to receive an internally threaded adjustment sleeve 24 which acts through an upper spring seat collar 26 to vary the compressive strength of the spring 19.

A working plate 27 is adapted to be attached to the under side of the attachment plate 12 for rotational movement by means of pins 28, locking pins 29, and a locking collar 31. The pins 28 project down from the attachment plate for engagement in apertures 32 provided in the working plate; and the locking pins 29 project up from the working plate and are formed with grooves 33 adapted to receive the flange 34 of the locking collar. The attachment plate and locking collar are slotted at 36 and 37 respectively to receive the locking pins.

The plate 27 is formed with a plurality of slots 38, each of which is adapted to receive the upright portion 39 of an abrasive holder 41. The holders 41 are held in position by means of screws 42 and are grooved along their sides at 43 to receive the ends of an abrasive strip 44 which is held against displacement by clips 45 formed of spring wire and pivotally mounted at 46. While the holders illustrated in the drawing are adapted for use in grinding and polishing flat valve seats, other forms may readily be mounted on the plate for use in finishing tapered valve seats. When employed in the finishing of flat valve seats, the bottom of each of the holders 41 is preferably formed convex to provide a line contact between the abrasive strips and the work.

A centering point 47 is provided on the end of the shaft for use in aligning the work in the machine, and a spring pressed ball 48 is provided in the attachment plate for engagement in notches 49 formed in the locking collar 31.

The attachment plate 12 and the locking collar 31 are formed with aligning slots 49 adapted to receive a spring locking member 51 to hold collar in position on the attachment plate.

5 In the operation of the apparatus thus described, the shaft 8 is adapted to be rotated by a drill press or the like and a downward pressure is exerted upon the shaft to place the spring 19 under compression. Rotational movement is 10 transmitted from the shaft to the working plate 27 by means of the driving plate 14 engaging the projections 16 formed on the attachment plate 12. As it is very difficult to align the work at exactly right angles to the axis of the shaft 15 8, I have provided the flexible connection between the shaft and the working plate 14 in which, the downward pressure upon the shaft is directed to the working plate through a one point contact provided by the pivot point 17 and the rotational movement is through the driving plate 14 and attachment plate 12. The pressure of the abrasive strips 44 upon the work may 20 readily be varied by turning the adjustment sleeve 24.

25 While I have shown my invention in but one form, it is obvious to those skilled in the art that it is not so limited but is susceptible of various changes and modifications without departing 30 from the spirit thereof; and I desire, therefore, that only such limitations shall be placed thereupon as are imposed by the prior art.

I claim:

1. In a grinding and polishing apparatus, a driving shaft, an attachment plate mounted for axial movement on said driving shaft, a compression spring mounted on the driving shaft to yieldably resist an axial movement of the attachment plate along the driving shaft, a pivot point interposed between the compression spring and the attachment plate, a working plate, work finishing elements mounted on the working plate, clip means for holding strips of abrasive material on the work finishing elements, means for detachably connecting the working plate to the attachment plate and means for varying the resistance offered by the compression spring when the attachment plate moves inwardly. 5 10 15

2. In a grinding and polishing apparatus, a driving shaft, an attachment plate mounted for axial movement on said driving shaft, spring means to yieldably resist an axial movement of the attachment plate along the driving shaft, a pivot point interposed between the spring means and the attachment plate, a working plate, a work finishing element mounted on the working plate, means for detachably connecting the working plate to the attachment plate and means for varying the resistance offered by the spring means when the attachment plate moves inwardly. 20 25
